UNITED STATES PATENT OFFICE.

WALTER F. GAGE, OF SMITH, NEVADA.

TOOTHPICK HOLDER.

Application filed October 4, 1926. Serial No. 139,460.

The invention relates to a dispensing device, and more especially to the class of tooth pick holders and dispensers.

The primary object of the invention is the provision of a device of this character, wherein a bunch or group of tooth picks can be conveniently held and at all times one of the latter partially extended from the device, so that the same can be conveniently dispensed therefrom to a user, the bunch or group of tooth picks within the device being protected from dust and other foreign matter and also relieved from the handling of the same, so that they will be thoroughly sanitary.

Another object of the invention is the provision of a device of this character, wherein tooth picks carried thereby will be shielded and dispensed singly in successive order, the device being of novel form so that at all times a part of one of the tooth picks held therein will be partially exposed so that it can be conveniently grasped for the removal of the same from the device for use.

A further object of the invention is the provision of a device of this character, wherein the container for the tooth picks is held and supported in a novel manner, whereby it may be adjusted relative to the base of the device to vary the exposure of a single tooth pick from the group held, to enable such exposed tooth pick to be readily and conveniently grasped when it is desired to use the same, the tooth picks being successively projected singly until the entire number held by the device are used.

A still further object of the invention is the provision of a device of this character which is extremely simple in construction, possessing but few parts, thoroughly reliable and efficacious in its purpose, durable, neat and attractive in appearance, readily portable, thoroughly sanitary, and inexpensive to manufacture.

With these and other objects in view, the invention consists in the features of construction, combination and arrangement of parts, as will be hereinafter more fully described in detail, illustrated in the accompanying drawing, disclosing the preferred embodiment of the invention, and pointed out in the claims hereunto appended.

In the accompanying drawing:

Figure 1 is a side elevation of a dispenser

and holder for tooth picks, constructed in accordance with this invention.

Figure 2 is a top plan view of the bracket showing the tooth pick holder or container removed.

Figure 3 is a vertical longitudinal sectional view through the tooth pick holder detached from the device.

Similar reference characters indicate corresponding parts throughout the several views in the drawing.

Referring to the drawing in detail, the device illustrated, comprises a base 5 of substantially conical formation and of a size to have the proper weight and area for effecting a proper bearing for the said device so as to eliminate the falling over or otherwise displacement of the same when in use.

Formed with and rising centrally at the apex of the base 5 is a vertical standard 6 in the form of a rod, having the required length or height from the base. Adjustably supported upon the standard 6 is a bracket having a coupling sleeve 7 at one end of an arm 8, the latter being designed to extend laterally at right angles to the axis of the standard 6, while the sleeve 7 slidably embraces said standard and has fitted therein a set screw 9 so that the bracket can be secured on the standard 6 in any desired adjusted position relative to the length or height of said standard. The bracket has formed on its arm 8 a closed yoke 10 in the form of a ring in which is removably fitted the tooth pick holder or container 90 hereinafter more fully described.

The holder or container for the tooth pick comprises a hollow tapering body 11 open at its smaller end and closed at its opposite larger end, the body being preferably made from glass, although the same may be made from any other suitable material and the formation thereof can be varied if desired. The smaller open end of the body 11 is externally reduced and formed with screw threads 12 for engagement with companion screw threads 13 internally of the rim 14 of a removable head or cap 15, which is likewise preferably made from glass. This head or cap 15 is provided with a central hole 16 opening through the same and merges with a funnel-shaped recess 17 formed centrally in the cap or head 15 to register with the open end of the body 11. The purpose of the recess 17 is to cause tooth 110

5 picks bunched or grouped within the body 11 to precipitate or gravitate toward the hole 16, which latter is of a size as to control the projecting of but a single tooth 10 pick 18 in successive order from the holder.

The holder for the tooth picks is inserted in the ring or loop 10 of the bracket so as to become seated therein as is shown in Figure 1 of the drawing. In this position the 10 cap 15 of the body 11 will be superposed relative to a step or riser 19 formed on and radially disposed upon the base 5. This 15 step or riser 19 limits the projecting of the tooth pick 18 through the hole 16 in the cap 15 of the holder, so that the projected portion of the tooth pick 18 can be readily grasped and drawn outwardly from the holder by a user.

The tooth picks are stored or placed within 20 the holder by removing the cap 15 and inserting the bunch or group of tooth picks through the open end of the body 11. Thereafter the cap or head 15 is screwed onto the body 11 and placed within the 25 bracket to be suspended in a manner as is clearly shown in Figure 1 of the drawing. The tooth pick 18 aligning with the hole 16 in the holder will drop through said hole 16 onto the step or riser 19, so that such tooth 30 pick will partially project from the holder, to be manually removed therefrom by a user. When the tooth pick projected is removed from the holder another tooth pick 35 will drop through the hole 16 onto the step or riser 19 and in this manner the tooth picks will be successively projected from the holder singly until the entire bunch or group are used.

It is, of course, to be understood that if desired the stand for the tooth pick container 40 can be dispensed with and the container used manually by shaking thereof to permit a single tooth pick to be dispensed therefrom.

From the foregoing it is thought that the 45 construction and manner of use of the device will be clearly understood and therefore a more extended explanation has been omitted.

What is claimed is:

1. A tooth pick holder of the character 50 described comprising a base having a standard, a bracket adjustably connected with said standard, a tooth pick container having a dispensing opening for emitting a portion of a tooth pick singly in successive 55 order, and means on the base in position relative to the opening to limit the exposure of a tooth pick when projected from the container.

2. A device of the character described 60 comprising a base, a standard on the base, a bracket adjustably connected to the standard and having a loop, a tapered tooth pick container having a removable cap at its smaller end provided with a central opening 65 to permit tooth picks within the container to be projected singly in successive order, and a riser formed on the base in confronting relation to the opening in the container to limit the exposure of a tooth pick when projected through said opening, the container being removably fitted in the loop or the bracket.

In testimony whereof, I affix my signature hereto.

WALTER F. GAGE.
